Inventor:

UNITED STATES PATENT OFFICE.

HENRY D. KLOTS, OF NEW YORK, N. Y.

SPINNING-SPINDLE.

SPECIFICATION forming part of Letters Patent No. 542,857, dated July 16, 1895.

Application filed December 10, 1894. Serial No. 531,353. (No model.)

To all whom it may concern:

Be it known that I, HENRY D. KLOTS, a citizen of the United States, residing in the city, county, and State of New York, have invented 5 certain new and useful Improvements in Spinning-Spindles, of which the following is a specification.

My invention relates to that class of spinning-spindles wherein the supporting and bearing tube of the spindle-blade is connected yieldingly to the spindle rail or base, with the object of obviating the vibration due to an unbalanced load.

My invention is particularly applicable to 15 spindles of this class in which the spindle-blade is constituted with a medial spring to co-operate with the yielding connection of the bearing, and also those in which the step for the spindle-blade is detached from the supporting and bearing tube; but it is also applicable to those in which the bolster and step bearings are combined in an integral tube.

Among the objects of my invention are to 25 simplify and improve the means of connecting the supporting and bearing tube yieldingly to the rail or base to increase and improve the oil supply for the spindle, to provide a better step for the spindle-blade when an independent step is used, and to improve 30 the yielding connection of the tube and rail or base with respect to the "spring-spindle" when used. I attain these and other important ends by my invention, of which the following is a detailed description.

35 Reference is to be had to the accompanying drawings, forming part of this specification, in which like parts are denoted by the same letters in all the figures.

Figure 1 is a side elevation of a spinning-spindle embodying my invention. Fig. 2 is 40 plan view of the same. Fig. 3 is a sectional elevation on the line 3 3, Fig. 4. Fig. 4 is a sectional plan view on the line 4 4, Fig. 3, parts being taken away.

45 A denotes the spindle-blade, which, in this example of my invention, is constituted with a reduced portion forming a spring B' intermediate the upper bobbin-holding and lower bearing portions of the blade.

50 B denotes the tube which supports the spindle-blade laterally and forms a bolster-bear-

ing therefor, but which tube I have here shown as independent of the step C on which the foot of the spindle-blade rests.

I form the supporting and bearing tube B 55 with an annular flange D and connect the tube yieldingly to the base-piece E, which is to be attached to and becomes practically part of the rail, by forming said base-piece E with a preferably circular box F to receive 60 and loosely contain the flange D and interposing metallic or non-metallic flexible packing-rings G H as cushions between the flange D and the bottom of the box F and the flange D and the cover I of the box. 65

I by preference construct the cover I to screw down into the box F, so as to tightly close the same and compress the packing-rings G H as tightly as may be required. I find in practice that this arrangement of cushions 70 co-operates with the spring B' of the spindle-blade in a peculiar manner to effectually remove all injurious vibrations of the spindle.

I form the base-piece E with a chamber K 75 below the box F to inclose the lower ends of the spindle and the tube B and hold a large supply of oil, and to the same end I form the box-cover I with a neck L surrounding the upper end of the tube B, the flange D and the 80 tube B being apertured to form oil-passages leading to the bearing-surfaces. Further, I rest the independent step C loosely upon a yielding cushion M in the bottom of the oil-chamber K, and I concave the bearing N of 85 said step on a sphere having its center substantially in the center of the packing-rings G H, so that said step need not play laterally with the lateral yielding of the spindle, as the tube B swings on its cushions almost as though 90 swiveled.

As a convenient means for holding the spindle-blade in its bearing, while readily allowing its removal, I form the box-cover I with an annular ring O to receive the flange 95 P on the lower end of the spindle-whirl, and pivot upon said ring a semiannular plate O', having a recess O² in its free end to swing over and retain the whirl-flange P, the recess O² engaging a headed stud O³ on the ring O. 100

I claim as my invention—

1. The combination, with the spindle-blade

- and its supporting and bearing tube provided with an annular flange, of a base-piece formed with a circular box to contain said flange, a detachable cover to be screwed upon said box, formed with a neck to surround the tube, and cushions compressed between said annular flange and the bottom and the cover of the box, substantially as hereinbefore set forth.
- 10 2. The combination, with the spindle blade constituted with a spring intermediate its bobbin-holding and bearing portions, and its supporting and bearing tube provided with an annular flange, of a base-piece formed with a box to contain said flange, a cover for said box and cushions interposed between said flange and the bottom and the cover of
- 15 the box, substantially as hereinbefore set forth.
3. The combination, with the spindle blade 20 and its whirl having a flange and the spindle-bearing, of a flange retaining piece pivoted at the side of the spindle and having a slot in its free end and a fixed headed stud to engage said slot and hold said retaining piece and 25 hence whirl vertically and laterally, substantially as hereinbefore set forth.

In testimony whereof I, the said HENRY D. KLOTS, have hereunto set my hand this 16th day of November, 1894.

HENRY D. KLOTS.

In presence of—

CLARENCE L. BURGER,
FRED C. EWING.
